COMBINED SWIMMING POOL AND ENCLOSURE

Joseph Diemond, Simsbury, and Melvin Y. Gershman,
West Hartford, Conn., and Norbert A. Vangness,
Longmeadow, Mass., assignors to Coleco Industries,
Inc., Hartford, Conn.

Filed Aug. 25, 1969, Ser. No. 18,829

Term of patent 14 years

Int. Cl. D25—99

U.S. Cl. D13—1

FIG. 2

FIG. 3

FIG. 4

FIG. 5

FIG. 1 is a perspective view of a combined swimming pool and enclosure showing our design;

FIG. 2 is a side elevational view thereof to a slightly enlarged scale;

FIG. 3 is a side elevational view of the opposite side thereof;

FIG. 4 is an end elevational view thereof, the opposite end being a mirror image thereof;

FIG. 5 is a plan view thereof; and

FIG. 6 is a fragmentary perspective view of another embodiment of a combined swimming pool and enclosure showing our design as adapted to a structure of greater dimension.

We claim:

The ornamental design for a combined swimming pool and enclosure, as shown and described.
